UNITED STATES PATENT OFFICE.

JOHN L. SALE, OF SAN FRANCISCO, CALIFORNIA.

DESIGN FOR A SOUVENIR BADGE.

SPECIFICATION forming part of Design No. 22,964, dated December 12, 1893.

Application filed November 14, 1893. Serial No. 490,960. Term of patent 3½ years.

To all whom it may concern:

Be it known that I, JOHN L. SALE, a citizen of the United States, residing in the city and county of San Francisco, State of California, 5 have invented and produced a new and original Design for a Souvenir Badge, of which the following is a specification, reference being had to the accompanying drawings, showing a part thereof.

Figure 1 is a view of one side of my souvenir badge. Fig. 2 is a view of the opposite side.

The leading feature of my design consists of embossed cameo or intaglio representations 15 upon the opposite sides of an essentially rectangular surface having irregular offsets at one end and an oval head at the opposite end.

A is the rectangular outline having irregular notches B at one end, and a head C at the 20 opposite end in the form of an oval or ellipse, the longest diameter of which is transverse to the rectangle, and the curvature of one side of the ellipse is connected with the straight

sides of the rectangular portion by a concave neck. The inner portion of the ellipse is cut 25 away in the form of two intersecting circles. Upon one side of the rectangular portion is a raised or intaglio figure of a building having central and end towers, and upon the opposite side of the same is a figure formed in the 30 same manner, of an arm or channel of the sea, with the sun in the central distance just appearing above the surface of the water. Upon the left side of the channel is a representation of a fort and upon the right side a representation of rocks.

What I claim is—

The design for a souvenir badge herein shown and described.

In witness whereof I have hereunto set my 40 hand.

JOHN L. SALE.
